UNITED STATES PATENT OFFICE.

CHARLES A. ALBERT, OF ASPINWALL, PENNSYLVANIA.

CURTAIN-POLE.

SPECIFICATION forming part of Letters Patent No. 769,141, dated September 6, 1904.

Application filed April 26, 1904. Serial No. 204,999. (No model.)

To all whom it may concern:

Be it known that I, CHARLES A. ALBERT, a citizen of the United States, residing at Aspinwall, in the county of Allegheny and State 5 of Pennsylvania, have invented a new and useful Curtain-Pole, of which the following is a specification.

This invention relates to means for supporting lace curtains and other draperies, and has 10 for its object to provide an improved curtain-supporting pole capable of being supported in any of the common or well-known forms of brackets and provided with means for hanging a curtain upon the pole without employing 15 pins or similar fastenings.

It is furthermore designed to facilitate the engaging of a curtain with the pole and to secure a neat and attractive fit of these parts in a very simple and convenient manner.

20 With these and other objects in view the present invention consists in the combination and arrangement of parts, as will be herein-after more fully described, shown in the accompanying drawings, and particularly pointed 25 out in the appended claims, it being understood that changes in the form, proportion, size, and minor details may be made within the scope of the claims without departing from the spirit or sacrificing any of the ad- 30 vantages of the invention.

In the drawings, Figure 1 is a front elevation of a curtain-pole embodying the features of the present invention with a pair of curtains hung therefrom. Fig. 2 is an elevation 35 of the pole. Fig. 3 is a detail longitudinal sectional view thereof on the line 3 3 of Fig. 2. Fig. 4 is a cross-sectional view on the line 4 4 of Fig. 2. Fig. 5 is a detail perspective view of the clip for the support of the inter- 40 mediate portion of the spring element. Fig. 6 is a view similar to Fig. 4, showing a different arrangement of the pole and the curtain.

Like characters of reference designate corresponding parts in each and every figure of 45 the drawings.

The pole 1 of the present invention may be of any material and of any shape, but is preferably formed of wood and cylindrical as now in general use. In one side of the pole 50 there is formed a longitudinal groove or seat

2, preferably arcuate in cross-section, with a longitudinal set or series of sockets 3 formed in the back of the groove adjacent the opposite ends thereof.

Seated longitudinally within the groove or 55 seat 2 is an elastic element 4, preferably in the nature of a helical spring, which is provided at opposite ends with laterally-disposed fingers or projections 5, which are designed to be fitted within any of the individual sockets 3, the latter being preferably inclined in- 60 wardly toward the middle of the pole, with the fingers or projections correspondingly inclined, whereby the tension of the spring is sufficient to retain the hooked fingers or pro- 65 jections within the sockets. Each finger 5 has its shank portion inserted within the adjacent end of the helical spring and soldered or otherwise suitably connected thereto.

The curtain 6 may be applied to the pole be- 70 fore or after the latter has been placed in the supporting - brackets therefor. If the curtains are applied to the pole before the latter is supported upon the window - frame, the spring is removed and the upper end portions 75 of the curtain are placed across the grooved side of the pole. The spring is then placed across the curtains and in the groove, with the hooked terminals 5 engaged with suitable sockets 3, whereby the curtain is clamped 80 between the spring and the pole, and when the latter is fitted to the supporting-brackets with the groove at the back of the pole the curtains will hang in the usual manner with their upper end portions depending from the 85 pole and overlapping the back of the curtain.

To prevent the sagging of the middle por- 90 tion of the spring, there is an elastic clip 8, formed from a single strip of spring metal, of a size to snugly clamp upon the pole, with its lower end provided with an inturned lip 9 to embrace the spring and hold the same snugly in the groove against the weight of the spring.

In the arrangement shown in Figs. 1 and 4 95 the upper edges of the curtains hang down across the backs of the curtains and are thereby concealed; but if it is desired to expose the upper edge portions of the curtains they may be arranged as shown in Fig. 6, 100

wherein the pole is turned to have the groove 2 and the spring 4 at the under side thereof, with the curtain looped over the spring only instead of over the pole, the upper edges of 5 the curtains hanging down across the fronts thereof, so as to be exposed to view from within the room. In this arrangement of the pole and curtains the spring-clip 8 is exposed to view, while in the arrangement shown in 10 Figs. 1 and 4 it is concealed by the curtains which embrace the pole and the clip. While only one spring-clip 8 has been shown, it will of course be understood that any number of 15 these clips may be employed, according to the length of the pole and the weight of the spring and curtains.

From the foregoing description it is apparent that the device of the present invention is exceedingly simple and effective for the 20 support of lace curtains, portières, and similar draperies without damage thereto by the engagement of pins therewith. Moreover, the present pole is capable of being supported by any of the ordinary forms of brackets, and the 25 curtains may be readily applied and removed and when connected to the pole will hang therefrom in a very attractive manner.

Having thus described the construction and operation of my invention, what I claim as new, 30 and desire to secure by Letters Patent, is—

1. A curtain-pole having a longitudinal curtain-receiving groove provided at opposite ends with sets of sockets, and a longitudinally-elastic curtain-holding element set within the 35 groove and having lateral terminal projections for adjustable engagement with the sockets of the groove.

2. A curtain-pole having a longitudinally-elastic curtain-clamping element disposed longitudinally of the pole with its ends fixed thereto, the intermediate portion of the clamping element between its fixed ends being separate from the pole and capable of being drawn away therefrom to receive a curtain 45 between the clamping element and the pole.

3. A curtain-pole having a longitudinally-elastic curtain-clamping element disposed longitudinally thereof with its ends fixed to the pole and capable of adjustment thereon to

take up lost tension, the intermediate portion 50 of the clamping element between its fixed ends being separate from the pole and capable of being drawn away therefrom to receive a curtain between the clamping element and the pole. 55

4. A curtain-pole having opposite longitudinal sets of sockets, and a longitudinally-elastic clamping element having its ends formed for adjustable engagement with the respective sets of sockets to take up lost tension therein, 60 the intermediate portion of the clamping member between its fixed ends being separate from the pole and capable of being drawn away therefrom to receive a curtain between the clamping member and the pole. 65

5. A curtain-pole having a helical spring applied longitudinally thereto with its terminals secured to the pole and the spring under tension, the intermediate portion of the spring being separate from the pole and capable of being drawn away therefrom to receive a curtain between the spring and the pole. 70

6. A curtain-pole provided with opposite longitudinal sets of sockets, and a helical spring having lateral terminal projections capable of interchangeable engagement with the sockets of the pole, the intermediate portion of the spring between the projections being separate from the pole and capable of being drawn away therefrom to receive a curtain 75 between the spring and the pole.

7. A curtain-pole having a longitudinal curtain-receiving groove therein and provided with longitudinal sets of sockets in the back of the groove at opposite ends thereof, a helical spring to fit within the groove and provided with terminal lateral projections for interchangeable engagement with the respective sets of sockets, and a spring-clip embracing the pole and having a terminal lip to embrace 85 the spring. 90

In testimony that I claim the foregoing as my own I have hereto affixed my signature in the presence of two witnesses.

CHARLES A. ALBERT.
